F. KULHAWY

LOUD SPEAKER

Filed March 18, 1926

Inventor:
Ferdinand Kulhawy
by Myron P. Saenger
Attorney

UNITED STATES PATENT OFFICE.

FERDINAND KULHAWY, OF GUTTENBERG, NEW JERSEY.

DESIGN FOR A LOUD SPEAKER.

Application filed March 18, 1926. Serial No. 16,964. Term of patent 3½ years.

To all whom it may concern:

Be it known that I, FERDINAND KULHAWY, citizen of United States, residing in Guttenberg, county of Hudson, and State of New Jersey, have invented a new, original, and ornamental Design for a Loud Speaker, of which the following is a specification, reference being had to the accompanying drawings, forming a part thereof.

Fig. 1 is a front elevation of the embodiment of my design;

Fig. 2 is a side view thereof.

I claim:

The ornamental design for a loud speaker substantially as shown.

FERDINAND KULHAWY.
